UNITED STATES PATENT OFFICE.

FRANK H. POEPPELMEIER, OF DAYTON, OHIO, ASSIGNOR OF ONE-FOURTH TO LAWRENCE A. POEPPELMEIER, ONE-FOURTH TO VINCENT E. POEPPELMEIER, AND ONE-FOURTH TO JOHN L. WEIGAND, ALL OF DAYTON, OHIO.

TYPE-DISTRIBUTING MACHINE.

Application filed March 16, 1925. Serial No. 15,987.

This invention relates to new and useful improvements in type distributing machines.

It is the principal object of my invention to provide automatic means for sorting type in groups of like characters regardless of the nature of the character and to deposit the sorted type in individual compartments. My invention thus supplants the laborious and less efficient method of manually sorting type which has been set up, into groups of like characters.

It is a further purpose of my invention to provide for employment in conjunction with the sorting device, a calendar device to receive the type in lines as it is removed from the form and to feed the type automatically into the sorting device without the attention of the operator.

In the accompanying drawings, Figure 1 is a partial plan view of my type distributing machine, one half of which is taken in the plane of the line A—A of Figure 2, and the remainder in the plane of the line B—B of Figure 2. Figure 2 is an elevational view, partly in section, taken on the line 2—2 of Figure 1. Figure 3 is a perspective view of the detector operating disc, actuating eccentric. Figure 4 is a perspective view of the ejector mechanism, operating disc. Figure 5 is a detail view of one of the detector and ejector units. Figure 6 is a sectional view taken on the line 6—6 of Figure 7, through the top of one of the sorted type receiving compartments. Figure 7 is a side view of the upper end of one of the type receiving compartments. Figure 8 is a plan view of the assorted type calendar device. Figure 9 is an enlarged view taken through the calendar device on the line 9—9 of Figure 8. And Figure 10 is an elevational view of the gearing and type disc drive means.

Referring to the accompanying drawings, the numeral 1 designates a pedestal frame having a flanged base 2. Rotatably mounted upon the upper end of the frame 1, is a sleeve 3 having on its periphery a flange 4 to the upper face of which there is secured a type disc 5, and to its lower face a worm gear 6 is attached. (See Figure 1.) The type disc 5 is formed adjacent to its periphery with equally spaced open slots 7 radially arranged and approximately the size of the type to be sorted.

Radially disposed in alignment with the slots 7 in the type disc 5, are detector plates 8 which are secured to the inner ends of detector slides 9. Each slide 9, together with its respective detector plate 8, is slidable in a radial slot 10 in a supporting ring 11 which is supported by arms 12 integral with the pedestal frame 1. Each detector plate 8 has in its inner face a female or sunken character 13 corresponding to one of the characters on the type to be sorted, there being one of these detector plates for each character, and preferably, ninety plates in all. Each detector slide 9 has integral with its upper face a projection 13^a, the upper end of which terminates in an inclined plane 14 whose function will be hereinafter described. The outer end of the slide 9 has a projection 15 to which is attached one end of a tension spring 16, the opposite end of which is attached to the ring 11. This spring maintains the slide in an inward position at all times.

The upright portion of the frame, which is tubular, receives a sleeve 17 which extends upwardly through the collar 3 and which has fixedly secured to it a disc 18 of slightly less diameter than the type disc 5. Secured to the periphery of the disc 18 is a cam plate 19 whose depending edge is sharply beveled. The lower end of the sleeve 17 is provided with a rectangular pocket 20 in which there is slidably fitted an eccentric block 21 which is free to travel transversely. (See Figures 2 and 3.)

The eccentric block 21 receives an eccentric 22 which is fixedly secured to an eccentric shaft 23 journaled in the frame 1 and to whose one protruding end there is secured a drive gear 24. When the shaft 23 and the eccentric 22 revolve, a reciprocating motion will be imparted to the sleeve 17. (See Figures 2, 3 and 10.)

The sleeve 17 receives a column 25 to the upper end which, and above the plate 18, there is secured an ejector disc 26. The column 25 is free to slide within the sleeve 17, and is given a vertical reciprocating movement in the same manner as the sleeve, by the following means. Provided in the lower end of the column 25 is a rectangular recess 27 into which there is fitted an eccentric block 28 that is free to travel transversely. In order to permit a sufficient travel of the block

- 28, openings 29 are provided in the sleeve 17 into which the block 28 may project when in its extreme lateral position without in any wise affecting the motion of the sleeve.
- 5 The block 28 receives an eccentric 29^a which is fixedly secured to an eccentric shaft 30 which, like the shaft 23, is journaled in bearings 31 secured to the frame 1. To the protruding end of this shaft 30 there is secured a gear 32 which meshes with the gear 24. The column 25 is thus given a reciprocatory vertical movement, and through the gears 24 and 32 the movements of the sleeve 17 and the column 25 are synchronized.
- 10 (See Figures 2, 3, 4 and 10.)
- The ejector disc 26 is provided with a depending rim 33 that has cut therein, radial slots 34 of the same angular spacing as the slots 7 in the disc 5. Each of the slots 34 receives an ejector 35, there being provided one ejector for each detector plate 8. The ejectors 35 are preferably L shaped; they are disposed in an inverted position, and each one has on its inner face, near its lower edge, a sharply inclined projection or tooth 36. The upper or outwardly projecting portion of the ejector is provided with a hole 37 which receives one end of a tension spring 38, the opposite end of which is secured to a small pin 39 attached to the disc 26. (See Figures 2 and 5.)
- In order that the ejector may travel in a vertical plane, I have provided in the vertical portion of said ejector 35 an elongated slot 40 which receives a ring 41. Due to the continuity of the rim 33, the ring 41 is employed to permit the various ejectors to be assembled upon it, whereupon the ejectors and ring are assembled on the rim 33, said ring being received by a groove 42 that is cut in the lower face of the rim 33. The ring 41 is then secured in the groove 42 by screws 43 at frequent intervals. (See Figures 2 and 5.)
- 45 The outer face of the rim 33 is provided with a band or circular plate 44 which is inclined substantially like the inclined surface 14 of the detector slide 9 and in contact with the latter, so that when the column 25 is reciprocated by the eccentric 29^a, all of the detector slides will be permitted to move inwardly and outwardly in co-ordinated relation with the movement of the disc 26.
- 50 Secured to the upper portions of the arms 12 is a circular plate 45 having attached to its upper face a number of receptacles 46 for the sorted type. These receptacles are arranged in circular order in radial alignment with the detector plates 8 and under the slots 7 in the disc 5 to receive the type 47 therefrom. In order that the sorted type may not fall into these receptacles, I have provided at the upper end and on each side of each receptacle, two flat springs 48, 49 having their lower ends riveted or

otherwise secured to the sides of the receptacle. The upper or free ends of the springs 48 enter slots 49 in the sides of the receptacles and protrude into the interiors of the latter, so that the last type 47 is firmly held in place with its upper face in the plane of the lower surface of the disc 5. (See Figures 5, 6 and 7.)

55 My method of automatically feeding assorted type into the disc 5 will now be described. Mounted upon a bracket 50 integral with the ring 11, is a stud 51 having on its central portion a bearing collar 52 upon which there is rotatably mounted a disc or plate 53. (See Figure 9.) The plate 53 has formed upon its upper face a rim 54 within which is confined a coiled steel spring 55 whose outer end is secured to the rim 54 and whose inner end is attached to the upper end of the stud 51, so that the disc 53 will be rotated counter-clockwise by the spring 55.

60 Radially mounted upon the upper face of the disc 53 is a number of type receiving chutes 56 of rectangular section and having openings in their lower ends registering with the slots 7 of the disc 5. Each of these chutes 56 is provided on its outer face, adjacent to the disc, with a hole to receive one end of a release pin 57. These pins 57 are mounted upon the free ends of springs 58, with a portion of each pin projecting beyond its respective spring. The opposite end of each spring is secured to the periphery of the disc 53 in such a manner that the pin is constantly under spring tension, tending to force it inwardly, but held in an outward position by the type within the chutes 56. (See Figures 8 and 9.)

65 It is the function of these pins to engage a stop 59 secured to the bracket 50 when the pins are in their outward positions, but to disengage said stop when the last assorted type leaves that particular chute, thus permitting the disc 53 to rotate and to bring the next full chute into a position over the receiving slot 7 in the disc 5. The upper end of each chute 56 is provided with a cover plate 60 having on one end a tongue 61 received by a hole 62 in the chute 56 and whose opposite end has a similar tongue 64 received by an open slot 65 in the chute and held therein by a spring 66. The free end of this spring is formed with a hook portion 67 to engage the plate 60, while its opposite end is secured to the chute. (See Figure 9.)

70 Projecting through a hole in said cover plate 60 is a vertical rod 68 having attached to its lower end within the chute 56, a rectangular plate 69. Between the cover 60 and the plate 69 is a compression spring 69^a to force the plate downwardly for the purpose of insuring the entrance of the type 47 into the slots 7 in the disc 5. To prevent the rod 68 from passing downwardly

through the cover plate 60; I have provided a stop 70 on its upper end. (See Figure 9.)

The means for operating the various units 5 of my device will now be described. Mounted upon the base 2 of the frame 1 is an electric motor 71 having upon its shaft a pinion 72 which engages the gear 24 upon the eccentric shaft 23. This gear 24 in turn meshes 10 with the gear 32 upon the eccentric shaft 30. Mounted upon a shaft 73 journaled in brackets 74, 74 cast integral with the frame 1, is a gear 75 which meshes with an idler 76 that also meshes with the gear 32. Also mounted 15 upon this shaft 73 is a pin plate 76^a and a lock plate 77 which, together with the gear 78, constitute a Geneva gear that is familiar to those versed in mechanics. (See Figures 2 and 10.)

20 The gear 78 is secured to the face of a gear 79, both of said gears being freely mounted upon a shaft 80 secured to a bracket 81 which is cast integral with the frame 1. The gear 79 meshes with a pinion 82 secured to a worm shaft 83, the projecting ends of which are journaled in brackets 84, 84 cast integral with the frame 1. Mounted upon the shaft 83 is a worm 85 that meshes with the worm gear 6. I do not desire to be limited to the 25 power means which I have shown and described for operating the various units of my type distributing machine, since any other suitable power means may be employed for this purpose if desired.

35 The operation of my type sorting device will now be described. When the motor 71 turns the gears 24 and 32, it will cause the eccentrics 22 and 29^a to rotate. The position of these eccentrics is so timed that as the column 25 moves upwardly, the plate 44 will also be moved upwardly to permit the detector slides 9 to be drawn inwardly by the tension springs 16. The characters on the projecting ends of the type 47 will then engage the detector plates 8 secured to the inner ends of the slides 9; and if the character on a particular type coincides with the indented character 13 on the detector plate 8 which it engages, there will be a further inward movement of the slide which carries that plate. This inward movement of the detector slide will be sufficient to cause the upper edge of the detector plate 8 which it carries, to engage and force inwardly the pending end of the ejector 35 a sufficient distance to cause the projection 36 thereon to come under the lower edge of the cam plate 19. At this time the plate 19 will start its downward movement, pressing the ejectors 35 downwardly against those particular type 47 which have fully coincided with the indented characters 13 on the detector plates 8 to force them into the receptacles 46.

When the sorted type have been ejected 65 into the receptacles 46, the disc 26 will be

drawn downwardly to move the slides 9 outwardly through the engagement of the inclined plate 44 with the inclined faces of the projections 13^a on said slides. At the same time the cam plate 19 and the ejectors 35 70 which it has engaged, will be moved upwardly by the disc 18 and springs 38 respectively; and at that interval of time when the ejectors 35 are raised above the slots 7 in the disc 5 and all of the detector plates 8 are held out 75 of contact with the type 47, the said disc 5 is indexed by the Geneva gear an amount equal to the angular spacing of the slots 7 in the disc, or sufficiently to bring the succeeding slots into a position under the feeding 80 mechanism. This cycle of operations will continue until all of the type 47 carried by the plate 53 are sorted.

Having described my invention, I claim:

1. In a type distributing machine, the combination with a series of type receiving receptacles, of a type carrier movable over said receptacles and adapted to bring the type into registry with them, slides movable toward said type carrier and having on their inner ends sunken characters corresponding to the characters on said type, means for moving said slides into engagement with the type carried by said carrier, and means controlled by the inward movement of the slides 90 to eject into said receptacles, the type whose characters coincide with the sunken characters on the slides.

2. In a type distributing machine, the combination with a series of type receiving receptacles, of a type carrier movable over said receptacles and adapted to bring the type into registry with them, slides movable toward said type carrier and having on their inner ends sunken characters corresponding to the characters on said type, means for moving said slides into engagement with the type carried by said carrier, an ejector for forcing said type from the carrier to the receptacles, and means controlled by the inward movement of a slide after its sunken character coincides with a like character on a type, to position the ejector for engagement with that type for the purpose specified.

3. In a type distributing machine, the combination with a series of type receiving receptacles, of a type carrier movable over said receptacles and adapted to bring the type into registry with them, slides movable toward said type carrier and having on their inner ends sunken characters corresponding to the characters on said type, means for moving said slides into engagement with the type carried by said carrier, an ejector for forcing a type from the carrier to a receptacle, disengageable means for forcing the ejector against the type to eject it into a receptacle, and means controlled by the inward movement of a slide after its re-

cessed character registers with a like character on a type, to place the ejector in engagement with the ejector operating means, for the purpose specified.

5. In a type distributing machine, the combination with a series of type receiving receptacles, of a type carrier movable over said receptacles and adapted to bring the type into registry with them, pivoted longitudinally movable ejectors for forcing said type into the receptacles, means into engagement with which the ejectors are adapted to be shifted, for longitudinal movement by said means into engagement with the type, and slidable means having recessed characters for engagement by said type to press an ejector into engagement with the ejector moving means when the character on a type comes into registry with a corresponding recessed character on the slidable means.

5. In a type distributing machine, the combination with a series of type receiving receptacles, of a type carrier movable over said receptacles and adapted to bring the type into registry with them, pivoted longitudinally movable ejectors for forcing said type into the receptacles, projections on said ejectors, means for engaging said projections to move the ejectors into engagement with the type, and slidable means having recessed characters for engagement by said type to shift an ejector a sufficient distance to bring its projection into the path of movement of the ejector moving means when the character on a type comes into registry with a corresponding recessed character on the slidable means.

6. In a type distributing machine, the combination with a series of type receiving receptacles, of a type carrier movable over said receptacles and adapted to bring the type into registry with them, slides having recessed characters corresponding to the characters on said type and adapted to engage the latter, pivoted longitudinally movable ejectors for forcing said type into the receptacles, means into engagement with which the ejectors are adapted to be moved, for longitudinal movement by said means into engagement with the type, reciprocating means for normally holding said slides out of engagement with said type, and means for drawing said slides into engagement with the type when the reciprocating means are withdrawn from them, and to draw said slides into engagement with the ejectors to press the latter into contact with the ejector moving means when the characters on the type come into registry with corresponding recessed characters on said slides.

7. In a type distributing machine, the combination with a series of type receiving receptacles, of a type carrier movable over

said receptacles and adapted to bring the type into registry with them, slides having recessed characters corresponding to the characters on said type and adapted to engage the latter, pivoted longitudinally movable ejectors for forcing said type into the receptacles, means into engagement with which the ejectors are adapted to be moved, for longitudinal movement by said means into engagement with the type, said slides having inclined projections, a reciprocating member having an inclined part adapted to engage the inclined projections on said slides to hold the latter out of engagement with said type, and means for drawing said slides into engagement with the type when the reciprocating means are withdrawn from them, and to draw said slides into engagement with the ejectors to press the latter into contact with ejector moving means when the characters on the type come into registry with corresponding recessed characters on said slides.

8. In a type distributing machine, the combination with a series of type receiving receptacles, of a type carrier movable over said receptacles and adapted to bring the type into registry with them, slides having recessed characters corresponding to the characters on said type and adapted to engage the latter, a reciprocating member for normally holding said slides out of engagement with said type, ejectors pivotally and longitudinally mounted on said reciprocating member for forcing said type into the receptacles, means into engagement with which the ejectors are adapted to be shifted for longitudinal movement by said means into engagement with the type, and means for drawing said slides into engagement with the type when the reciprocating member is moved away from them, and to draw said slides into engagement with the ejectors to press the latter in contact with the ejector moving means when the characters on the type come into registry with corresponding recessed characters on said slides.

9. In a type distributing machine, the combination with a series of type receiving receptacles, of a type carrier movable over said receptacles and adapted to bring the type into registry with them, slides having recessed characters corresponding to the characters on said type and adapted to engage the latter, a reciprocating member for normally holding said slides out of engagement with said type, L shaped ejectors, each ejector being provided in its vertical portion with an elongated slot, a pin carried by the reciprocating member projecting through said slot, a spring connected between the horizontal portion of the ejector and the reciprocating member, a projection on each ejector, a cam plate adapted to engage said projections to force the ejectors into engage-

ment with said type, and springs for drawing the face ends of said slides into engagement with said type, and adapted to draw the slides still further inwardly for engagement with the inner ends of said ejectors to force them in the path of the inward movement of the cam plate, for the purpose specified.

10. In a type distributing machine, the combination with a series of radially arranged type receiving receptacles, of a type carrier horizontally rotatable over said receptacles to bring type into registry with them, vertically disposed ejecting means for forcing type from the carrier into said receptacles, and slideable means radially disposed with regard to the type in the carrier, and bearing recessed characters for co-incidence with corresponding characters on the type to control the type ejecting movement of said ejecting means.

11. In a type distributing machine, the combination with a series of radially arranged type receiving receptacles, of a type carrier horizontally rotatable over said receptacles to bring type into registry with them, vertically disposed ejecting means for forcing type from the carrier into said receptacles, slideable means radially disposed with regard to the type in the carrier and bearing recessed characters for co-incidence with corresponding characters on the type to control the type ejecting movement of the ejecting means, means for indexing the type carrier, and means for withdrawing the ejecting means and the slideable means from the carrier during the indexing operation.

12. In a type distributing machine, the combination with a series of radially arranged type receiving receptacles, of a type carrier horizontally rotatable over said receptacles to bring type into registry with them, vertically disposed ejectors for forcing type from the carrier into said recep-

tacles, slides radially disposed with regard to the type in the carrier and bearing recessed characters for co-incidence with corresponding characters on the type to control the type ejecting movement of said ejectors, and a reciprocating member on which said ejectors are mounted, adapted to engage the slides to move them away from the carrier after a type ejecting operation is concluded.

13. In a type distributing machine, the combination with a rotatable type receiving medium, of a type distributing device rotatable beneath said type receiving medium, means for feeding assorted type from the type receiving medium into the type distributing device, and means for bringing the type receiving medium into successive feeding positions over the type distributing device.

14. In a type distributing machine, the combination with a rotatable medium, assorted type receiving receptacles carried thereby, of a type distributing device rotatable beneath the receptacles carried by the rotatable medium, means for feeding assorted type from said receptacles into the type distributing device, and means for bringing successive receptacles into a feeding position with respect to said type distributing device.

15. In a type distributing machine, the combination with a rotatable carrier, assorted type receiving receptacles mounted in said carrier, of a type distributing disc formed with slots near its periphery rotatable under said carrier, means for feeding assorted type from said receptacles into the slots in said type distributing disc, and means for bringing said receptacles successively into feeding position over the slots in the type distributing disc.

In testimony whereof I have hereunto set my hand this 14th day of March, 1925.

FRANK H. POEPPELMEIER.
